UNITED STATES PATENT OFFICE.

JOHN N. HELTZEL, OF WARREN, OHIO.

ROAD FORM.

Application filed September 24, 1927. Serial No. 221,809.

The present invention relates to road form rails such as are employed in the building of concrete roads for defining the sides of the road, and one object of the invention is to provide a form rail having a tread which provides a single longitudinal line of contact for the wheels of bridges, finishing machines, and the like, as well as a single line of contact for strike-offs and similar implements, whereby by the contact between the rail and wheels or devices movable thereon is maintained without interference by sand, pebbles, stones or other particles on the rail tread and whereby such articles are shed off the rail tread.

Another object of the invention is the provision of novel bracing and stake receiving means on the rail.

A further object is the provision of novel means for binding the rail and stake together, and a still further object is to provide means which simultaneously with the binding of the rail and stake together will also create an expansive action between the tread and base flanges of the rail.

The invention has for another object the provision of novel means for simultaneously clamping or binding adjoining rails and corresponding stakes together and also obtaining an expansive action within the rails to secure them together in alinement.

A still further object is the provision of rail bracing, staking and binding means of simple, practical and efficient construction, which may be readily formed from sheet metal excepting the stakes.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein—

Figure 1 is an elevation of the improved form.

Fig. 2 is a cross section of one of the rails showing the bracing and binding means in end view.

Fig. 3 is a cross section on the line 3—3 of Fig. 1.

Fig. 4 is a horizontal section on the line 4—4 of Fig. 2.

Fig. 5 is a view corresponding with Fig. 2 illustrating a modification.

Fig. 6 is a perspective view of another modification.

Figs. 7, 8 and 9 are views corresponding with Fig. 2 depicting other modifications.

Fig. 10 is a section on the line 10—10 of Fig. 9.

The form rails are bent from sheet metal of suitable gage, and each rail has the vertical web 14, base or base flange 15 with an up-standing flange or lip 16, and tread or tread flange 17 with a depending secondary flange or lip 18. The bevelled tread is substantially the same as disclosed in my Patent No. 1,637,998, granted August 2, 1927, and provides a single line of contact immediately above the web 14.

The base 15 is wider than the tread 17, and they are connected by a brace 19 of suitable sheet metal which has its upper and lower ends overlapping and riveted, welded or otherwise secured to the lips or secondary flanges 16 and 18, preferably at the inner side thereof. One of the braces 19 may be located adjacent to each end of the rail and one or more braces may be provided at points between the ends of the rail. Said braces connecting the tread and base of the rail will strengthen same opposite to the web 14.

Each brace 19 has an outstruck or outwardly pressed portion 20 with an upper aperture 21 to receive a stake 22 driven downwardly through the brace into the ground or sub-base, the rail base 15 having an aperture 23 below the aperture 21 for the passage of the stake. The portion 21 is semi-circular in horizontal section so as to fit snugly against the stake 22, and the aperture 21 is of a size to snugly receive the stake, so that material falling over the tread of the rail will not drop down around the stake within the stake opening or socket. The portion 20 also provides a concaved seat for the stake.

A binding member 24, composed of a plate of suitable sheet metal, is slidable in the rail, and as shown is slidable in the adjacent end portions of adjoining alined rails to maintain said rails in alinement end to end. The member 24 has the upper edge portion 25 inclined to bear upwardly against the tread 17 of each rail, with the upper edge of the member 24 seating in the bend between the web 14 and tread 17, and the lower edge portion 26 of said member is inclined reversely and seats in the bend between the web 14 and base 15 of each rail. The member 24 has the outstanding portion 27 of V-shaped cross-section provid-

ing a ridge extending horizontally behind the stakes 22, and the member or plate 24 is thus of angular cross-section so that the member 24 is resilient in vertical and horizontal directions transversely of the rail. Wedges 28 are pressed outwardly from the ridge of the portion 27 to contact with the stakes 22 behind the braces 19, so that when the member 24 is driven behind the braces and stakes (toward the left in Fig. 4), the members 24 tend to separate the rail webs 14 and stakes 22, thereby clamping the stakes 22 against the portions 20 and bases 15. This will bind the rails and stakes together to prevent relative vertical movement thereof. At the same time, when the member 24 is driven between the webs 14 and stakes 22, said member is brought under compression, tending to flatten said member, and as a result the upper and lower edges of the member 24 are moved or forced apart against the tread and base of each rail. The member 24 is thus given a vertical expansive action so as to bring the upper and lower portions thereof tightly against the treads and bases of the rails, thereby creating a binding action between said member 24 and rails simultaneously with the binding of the rails and stakes together. This will securely bind the rails, stakes and member 24 together, to hold the rails together in alignment and in proper position on the stakes.

The member 24 has a striking lug 29 thereon near one end to receive the blows of a hammer or other implement for driving the member 24 in either direction, and it will be apparent that the member 24 may be retracted into one rail (the right hand rail as seen in Figs. 1 and 4) when the rails are separated and assembled, and said member may then be driven into the other rail when they are positioned end to end and the stakes 22 driven through the apertures 21 and 23. As the wedges 28 are driven into engagement with the stakes 22, as seen in Fig. 4, thereby clamping or binding the stakes and braces together, the pressure exerted on the intermediate portion of the member 24 will be transmitted upwardly and downwardly to the upper and lower edges of said member so as to force them tightly against the treads and bases of the rails, thereby binding the member 24 and rails together also. By driving the member 24 in the opposite direction this will relieve the pressure between said member and rails, as well as releasing the stakes 22. With this arrangement it is possible to simultaneously bind the rails and stakes together as well as binding the rails together through the joint member 24. The member 24 may be positioned to hold the rails in alignment with the stakes 22 loose so that the stakes may be driven or withdrawn while maintaining the rails in alignment end to end. When the member 24 is retracted the rails may be assembled or sep-

arated, and the stakes 22 may also be driven into place or withdrawn, and by a single operation, that of driving the member 24 into place, the rails, stakes and member 24 are bound together each to the others. The member 24 may also be moved to releasing position from the stakes while maintaining the rails in alignment, and it is unnecessary to remove the stakes, and the stakes may also be removed without releasing the member 24, thus providing advantages in building up and knocking down the form. When the member 24 is driven out of wedging contact with the stakes it is capable of sliding freely in the rails, but when it is driven into wedging contact with the stakes said member expands or spreads vertically so as to become tightly expanded between the treads and bases of the rails. The lug 29 striking the brace 19 will prevent the member 24 from being driven too far so as to pass completely from the corresponding rail, and will prevent the wedges 28 from passing beyond the stakes.

Fig. 5 shows a horizontal rail tread 17^a on which is bolted or otherwise secured an angle iron 30 having an upstanding flange above the rail web to support the wheels of bridges, finishing machines, etc., as well as strikeoffs and other implements on the rail with a single line of contact. The rail tread 17^a as well as the rail tread 17 above described may thus be made of considerable width, whereas it would be impractical to make the ordinary rail tread of unusual width because the surface would be too wide for the contact of the wheels of finishing and other machines, owing to the fact that sand, pebbles, stones and other particles would accumulate on such rail treads, whereas with the present invention a wide tread may be used with only a single line of contact between the tread and the wheel or implement moving thereon.

Fig. 6 illustrates an auxiliary tread 31 mounted on a horizontal rail tread 17^b, said auxiliary tread 31 being of triangular section, and may be formed of sheet metal or tubular stock, to provide a single line of contact and a beveled or inclined surface sloping outwardly from said line of contact. As shown, the inclined or bevelled portions are pressed downwardly, as at 32, for receiving clamping bolts or elements which fasten the auxiliary treads down on the rail treads.

Fig. 7 shows a portion 17^c bent back outwardly from the upper edge of the rail web 14^c, and having an outstanding flange 19^c to which the upper end of the brace 19^c is secured. The binding member 24^c has its upper end 25^c extending vertically into the pocket or groove between the web 14^c and portion 17^c. The doubled portion or bend between the web 14^c and portion 17^c provides a single line of contact for the wheel or device which moves on the rail.

Fig. 8 illustrates a rail the tread 17^d of

which is bevelled outwardly and inwardly so as to slope in opposite directions, whereby sand, pebbles, stones and other particles will be shed inwardly and outwardly. The tread 5 has a ridge formed by a rather sharp angle so as to provide a single line of contact for wheels and other devices movable on the rail. The binding member 24^a bears upwardly under the ridge of the tread and has a down-turned flange 25^a bearing against the inner portion of the tread 17^a.

Figs. 9 and 10 illustrate the use of oblique slots 28^a in the portion 27^a of the member 24^a through which the stakes 22^a pass when inserted down through the portions 20^a. The braces 19^a are secured to the flanges or lips 16^a and 18^a of the rail bases and treads 15^a and 17^a, respectively. The upper and lower edge portions 25^a and 26^a of the member 24^a 20 seat in the bends between the webs 14^a and the treads 17^a and bases 15^a. The same wedging action is provided when the member 24^a is driven longitudinally in one direction (toward the left in Fig. 10) with the stakes 22^a driven down through the braces 19^a, slots 28^a and rail bases 15^a. The inner edges of the slots 28^a as well as the wedges 28 provide oblique cam surfaces to contact with the stakes for binding the parts together.

30 Members 24, 24^a, 24^b and 24^c, and the like, may also be used in connection with braces and stakes between the ends of the rails, and said members when used with individual stakes may be of shorter length and need 35 have only a single wedge 28 or slot 28^a, the double wedges or slots being used at the rail joints.

Having thus described the invention, what is claimed as new is:—

40 1. Means adapted to be disposed in a concrete form rail and arranged to have a transverse compressive action in the rail, said means being constructed so as to exert a vertical expansive force when under transverse compression.

45 2. Means adapted to slide longitudinally in a concrete form rail and arranged to have a wedging action in the rail transversely of the rail, said means being constructed so as to exert a vertical expansive force when under transverse compression due to said wedging action.

50 3. A resilient member adapted to be positioned in a concrete form rail and constructed to receive a transverse compression force, said member being formed so as to exert a vertical expansive force when under transverse compression.

55 4. A resilient member adapted to slide longitudinally in a concrete form rail and constructed to have a wedging action in the rail transversely of the rail, said member being formed so as to exert a vertical expansive force when under transverse compression due to said wedging action.

5. A sheet metal member adapted to slide between the tread and base of a concrete form rail and having a cam portion between its upper and lower portions to create a wedging action transversely of the rail, said plate 70 being formed so as to expand vertically when under compression due to said wedging action.

6. The combination of a concrete form rail, and means therein adapted to receive a transverse compression force and constructed to expand vertically in the rail when under transverse compression.

7. The combination of a concrete form rail having a tread and a base, and a resilient 80 member between and contacting with said tread and base and slidably longitudinally of the rail, said member having a cam portion between the tread and base to contact with another portion to create a wedging action, 85 said member being formed to expand vertically when under transverse compression due to said wedging action.

8. The combination of a concrete form rail, a stake to engage the rail, and means to be disposed between the rail and stake and arranged to receive compressive force between said rail and stake and to expand vertically in the rail.

9. The combination of a concrete form rail 95 having a tread and a base, a stake to engage the rail, and a resilient member between and engaging said tread and base and having a cam portion to engage said stake, said member being slidably longitudinally of the rail and being formed to expand vertically when under transverse compression due to the wedging contact of said cam portion with the stake.

10. A concrete form rail having a tread 105 and a base, and a brace connected to said tread and base and having an outwardly pressed stake-receiving portion.

11. A concrete form rail having a tread and a base, and a brace connected to said tread and base and having an outwardly pressed stake-receiving portion, said portion having an upper aperture and a concaved portion below the aperture to fit the stake.

12. The combination of a concrete form 115 rail having a base, a tread and stake receiving means, and a member slidably engaging said base and tread and having a cam portion to engage a stake in said means.

13. The combination of a concrete form 120 rail having a base, a tread and stake receiving means, and a member slidably engaging said base and tread and having a cam portion to engage a stake in said means, said member being formed to expand vertically 125 when under transverse compression by the wedging action of said cam portion against the stake.

14. The combination of a concrete form 130 rail having a tread and a base, a brace con-

necting the tread and base and having a stake 5
socket, and means slideable between the rail
and a stake in said socket in contact with
said tread and base and adapted to receive
transverse compression force between said
stake and rail, said means being constructed
to expand vertically when under transverse
compression.

15. The combination of a concrete form
10 rail, a stake to engage the rail, means for
simultaneously binding the rail and stake
together and exerting a vertical expansive
force in the rail.

16. The combination of two concrete form
15 rails disposed end to end, stakes to engage
said rails, and means operable for simulta-
neously binding said rails and stakes together
and exerting a vertical expansive force in
said rails.

20 17. The combination of two concrete form
rails disposed end to end and having stake-
receiving means, and a joint member for the
rails adapted to simultaneously bind the
stakes and rails together and to expand ver-
25 tically within the rails.

18. The combination of two concrete form
rails disposed end to end and having stake-
receiving means, and a resilient joint mem-
ber slideable longitudinally in the rails and
having cam portions to engage the stakes 20
with a wedging action, said member being
formed to expand vertically in the rails when
subject to the wedging action.

19. The combination of two concrete form
rails disposed end to end and having treads 35
and bases, braces connecting said treads and
bases and having stake sockets, and a resili-
ent joint member slideable between said treads
and bases and having cam portions to engage
the stakes with a wedging action, said mem-
bers being formed to be expanded vertically 40
when subject to said wedging action.

20. A concrete form comprising a rail hav-
ing a web at its inner side and an outwardly
extending tread flange, and a single line con-
tact portion above said flange at the web
side of the rail. 45

In testimony whereof I hereunto affix my
signature.

JOHN N. HELTZEL.
